UNITED STATES PATENT OFFICE.

WILLIAM L. HUMMEL, OF CHICAGO, ILLINOIS.

TOOTHBRAH ATTACHMENT.

Application filed July 24, 1924. Serial No. 727,972.

To all whom it may concern:

Be it known that I, WILLIAM L. HUMMEL, a citizen of the United States, and a resident of Chicago, in the county of Cook and State 5 of Illinois, have invented a new and useful Improvement in Toothbrush Attachments, of which the following is a full, clear, and exact description.

My invention relates to improvement in 10 tooth brush attachments, and it consists in the combinations, constructions, and arrangements herein described and claimed.

An object of my invention is to provide an 15 attachment for tooth brushes by means of which the brush may be utilized for thoroughly and quickly cleaning plates of false teeth, particularly the upper plate.

A further object of my invention is to provide an attachment for tooth brushes having 20 an auxiliary brush member which can be quickly removed or attached to the tooth brush proper so as to permit of the latter being used in the ordinary manner or as a device for cleaning plates of false teeth.

25 Other objects and advantages will appear in the following specification, and the novel features of the invention will be particularly pointed out in the appended claims.

My invention is illustrated in the accompanying drawings forming a part of this 30 application, in which—

Figure 1 is a side view of a tooth brush proper with my improved attachment

Figure 2 is a plan view of the device

35 Figure 3 is a section along the line 3—3 of Figure 1, and

Figure 4 is a plan view of a modified form of the device.

In carrying out my invention I provide a 40 tooth brush such as that shown in Figure 1, having a handle 1 and bristles 2. The bristles of the brush are preferably arranged so that their ends form a curve as shown in the drawing.

45 The attachment consists preferably of an end cap having a flat body portion 3 arranged to bear on the top of the head 4, bearing the bristles and being provided with side flanges 5, which conform to the sides of the 50 head 4. Upwardly turned curved flanges 6 are provided. The end portion 7 is bent downwardly and then rearwardly as shown at 7^a in Figure 2. This end portion has a recess 8 for a purpose hereinafter described.

55 The end portion has backwardly extending flanges 9 which are bent underneath the

flanges 6 and which are designed to engage with the sides of the head.

The flanges 6 are arranged to hold a brush. The latter is preferably made of bristles 10 60 held by twisted wire 11. This brush is preferably curved as shown in Figure 2. The twisted wire has spring ends 12 which are arranged to enter between the opposed flanges 6 so as to frictionally hold the brush 65 in position. While I have described in detail my improved form of the invention, it is obvious that other forms might be used without departing from the spirit and scope of the appended claims. The recess 8 in the 70 flange 7^a straddles some of the bristles and permits the flange 7^a to be extended so as to prevent an upward movement of the cap while at the same time permitting the auxiliary brush to be brought closely to the end 75 of the tooth brush proper.

From the foregoing description of the various parts of the device the operation thereof may be readily understood.

The tooth brush may be used as an ordinary tooth brush for the cleaning of teeth. It is very difficult, however, with the ordinary tooth brush to clean a plate of false teeth, especially in the corners of the plate. By slipping the body portion 3 of the attachment over the head of the tooth brush until the parts have the position shown in Figure 1, the tooth brush is provided with a brush which will get into the corners and which will efficiently clean the plate. Furthermore, the body portion of the tooth brush itself can be used to clean the upper part of the plate while the corners are being cleaned, for by placing the tooth brush on the plate as shown in Figure 1 and giving it an oscillating motion the smaller brush will be caused to traverse the curved corner portions of the plate while the body portion of the tooth brush will move over the upper surface. This permits the plate to be cleaned 95 quickly. The attachment can be readily removed and replaced when needed.

It will be seen that I have provided an auxiliary brush which may be readily attached to a tooth brush for cleaning plates 100 of false teeth.

In Figure 4 I have shown a modified form of the device. In this form the brush consists of bristles 10^a on a roller 11^a which is carried on a twisted wire member 11^b. The 110 roller 11^a moves during the cleaning process and this tends to bring different portions

of the brush to bear at different times on the object to be cleaned, thus prolonging the life of the brush.

I claim:

5. 1. A tooth brush attachment comprising a cap having a portion arranged to frictionally engage the end of a tooth brush head, an auxiliary brush having spring arms, and means carried by said cap for detachably holding said spring arms.
- 10 2. A tooth brush attachment comprising a cap arranged to frictionally engage one end of the head of a tooth brush, and having a portion struck up therefrom, a brush head

of substantially cylindrical form, and means 15 for supporting said brush head, said means being arranged to be engaged and to be detachably held by said struck-up portion.

3. A tooth brush attachment comprising a removable cap arranged to slip on the end 20 of the head of a tooth brush, and having flanges for preventing lateral movement or movement at right angles thereto with respect to the head, a brush head, and means secured to said cap for maintaining said 25 brush head in advance of the end of the tooth brush and below the head.

WILLIAM L. HUMMEL.
